(57) CLAIM

The ornamental design for a toy tabletop, as shown and described.

DESCRIPTION

FIG. 1 is a top perspective view of a toy tabletop showing our new design;

FIG. 2 is a top view;

FIG. 3 is a bottom view;

FIG. 4 is a front view;

FIG. 5 is a rear view;

FIG. 6 is a left side view;

FIG. 7 is a right side view;

FIG. 8 is a partial close-up view taken from the upper right of the top perspective view of FIG. 1;

FIG. 9 is a partial close-up view taken from the upper left of the front view of FIG. 5;

FIG. 10 is a top perspective view of second embodiment of a toy tabletop; and,

FIG. 11 is a top perspective view of third embodiment of a toy tabletop.

In the drawings, the broken lines depict portions of the design that form no part of the claim.
